US0D1102371S

(12) **United States Design Patent** (10) **Patent No.:** **US D1,102,371 S**
(45) **Date of Patent:** **** Nov. 18, 2025**

(54) **BATTERY**

(71) Applicants: **HUIZHOU EVE POWER CO., LTD.**
Huizhou (CN); **EVE POWER CO., LTD.**, Jingmen (CN)

(72) Inventors: **Liming Huang**, Guangdong (CN);
Changfei Min, Guangdong (CN);
Rongwei Liu, Guangdong (CN);
Yuebin Xu, Guangdong (CN); **Wei He**,
Guangdong (CN)

(73) Assignees: **HUIZHOU EVE POWER CO., LTD.**,
Huizhou (CN); **EVE POWER CO., LTD.**, Jingmen (CN)

(**) Term: **15 Years**

(21) Appl. No.: **35/521,436**

(22) Filed: **Apr. 1, 2024**

(80) **Hague Agreement Data**

Int. Filing Date: **Apr. 1, 2024**

Int. Reg. No.: **DM/238002**

Int. Reg. Date: **Apr. 1, 2024**

Int. Reg. Pub. Date: **Jun. 28, 2024**

(30) **Foreign Application Priority Data**

Dec. 29, 2023 (CN) 202330870472.2
Dec. 29, 2023 (CN) 202330870473.7
Dec. 29, 2023 (CN) 202330870474.1
Dec. 29, 2023 (CN) 202330870475.6

(57) **CLAIM**

The ornamental design for a battery as shown and described.

DESCRIPTION

1.Battery
1.1: Front
1.2: Back
1.3: Left
1.4: Right
1.5: Top
1.6: Bottom
1.7: Perspective
1.8: Perspective
